UNITED STATES PATENT OFFICE.

JEAN ALEXANDRE LACÔTE, OF PARIS, FRANCE.

SCUTCHING OR FIBER-PREPARING MACHINE.

SPECIFICATION forming part of Letters Patent No. 701,058, dated May 27, 1902.

Application filed March 14, 1901. Serial No. 51,110. (No model.)

To all whom it may concern:

Be it known that I, JEAN ALEXANDRE LACÔTE, a citizen of the Republic of France, and a resident of Paris, France, have invented new and useful Improvements in or Relating to Scutching or Fiber-Preparing Machines, which improvements are fully set forth in the following specification.

This invention relates to a new form of scutching or fiber-preparing machine for converting into fiber ready for spinning or to be employed in spinning strips of vegetable substance which have been broken or prepared in some suitable manner, but preferably in the manner described in my application for Letters Patent, No. 51,109, of even date.

In the accompanying drawings, Figure 1 is a front elevation of a machine constructed in accordance with this invention. Fig. 2 is a side view of the same, and Fig. 3 is a plan.

Like letters indicate like parts throughout the drawings.

The machine comprises, essentially, two pressing devices *a* and *b*, *a* being movable and consisting of a drum or roller having a reciprocating as well as a rotary motion, and the other device, *b*, being stationary or fixed, but adjustable in every direction. This presser device *b* is adapted simply to bear against the drum or roller *a*.

The stalks to be treated are placed between the pressing devices, and by the rotation of the drum *a* they are drawn forward, transformed into fibers ready for treatment and containing no foreign matter. A drawing-pulley *c* is keyed upon a shaft *d*, which carries a cam *e*, into which projects a roller or stud *f* on a boss *g*, carried by a sleeve *h* on the shaft *i* of the drum. The former shaft *d* is provided with an endless screw *j*, which imparts motion to a worm-pinion *k* on a shaft *l*, and by a similar arrangement of endless screw and pinion this shaft *l* imparts motion to the shaft *i* of the drum *a*. The movable drum *a* is secured to the sleeve *h*, which is adapted to have rotary and rectilinear motion on the shaft *i*, to which it is slidably keyed. Reciprocating rectilinear

motion is imparted to the sleeve *h* and the drum *a* by means of the rotation of the shaft *i* and the cam *e*, which latter engages the roller *f* of the boss *g*. The movable drum *a* is provided with a series of transverse grooves *a'* throughout its length. The upper relatively fixed compressor is composed of a frame *b* *b'* *b''* *b'''*, of which frame *b* indicates the side bars suitably pivoted to lugs or brackets *r*, *b'* indicates two rails or cross-bars fixed near the outer ends of the side bars, *b''* indicates wires arranged closely together and the upper ends of which are clamped between the cross-bars *b'*, and *b'''* indicates a pair of cross-bars fixed to the inner ends of side bars *b* and between which the lower ends of the wires *b''* are clamped. The wires *b''* provide channels or grooves on the under face of the compressor-frame *b* *b'* *b''* *b'''* and the planes of which are parallel with those of the annular grooves of drum *a*. The said frame bears against drum *a* under its own weight or by that of weights *s*, suitably adjustable.

The stalks or stems may be supplied to the machine from a table or hopper, or they may be placed directly between the pressing devices.

Having now particularly described and ascertained the nature of my said invention and in what manner the same is to be performed, I declare that what I claim is—

In a scutching or fiber-preparing machine, the combination of a rotary longitudinally-shifting compressor-drum provided with transverse annular grooves, and a compressor-frame arranged above the said drum and pivoted relatively thereto, so as to rest on the drum, said frame being equipped, on the face adjacent the drum, with a plurality of closely-arranged wires, substantially as set forth.

In testimony whereof I have signed this specification in the presence of two subscribing witnesses.

JEAN ALEXANDRE LACÔTE.

Witnesses:

EMILE LEOBRET,
EDWARD P. MACLEAN.
